UNITED STATES PATENT OFFICE.

CHARLES DONAGHY, OF PHILADELPHIA, PENNSYLVANIA.

DESIGN FOR A COAL-HOD OR SIMILAR ARTICLE.

SPECIFICATION forming part of Design No. 33,202, dated September 11, 1900.

Application filed August 7, 1900. Serial No. 26,201. Term of patent 14 years.

To all whom it may concern:

Be it known that I, CHARLES DONAGHY, a citizen of the United States, residing at the city of Philadelphia, in the county of Philadelphia and State of Pennsylvania, have invented and produced a new and original Design for a Coal-Hod or Similar Article, of which the following is a specification, reference being had to the accompanying drawings, forming part hereof, in which—

Figure 1 is a side elevational view of a coal-hod or similar article of the design of my invention. Fig. 2 is an end view of the same. Fig. 3 is a top or plan view showing the configuration of the bottom, looking at the same from the inside, and the corrugated and ribbed body of the coal-hod.

The leading or material feature of my design consists of the shape or configuration of the coal-hod or similar article.

Referring to the drawings, *a* is the body, provided with an elongated throat *a'*, the wall of the body and throat being formed with corrugations and ribs arranged in the throat portion, so that the corrugations and ribs are disposed in vertical parallel courses

and the sides inclined in straight parallel courses to each other, the degree of inclination of the corrugations and ribs lessening in extent to the back *a''*, where they join each other, as clearly illustrated in Fig. 2 of the drawings.

b is the fluted bottom rim of the coal-hod or similar article, as clearly illustrated in Figs. 1 and 2, and *c* is the bottom, provided with grooves or recesses arranged in radial courses and extending from the periphery to the center, as clearly illustrated in Fig. 3 of the drawings.

Having thus described the nature of my invention, what I claim as new, and desire to secure by Letters Patent, is—

The design for a coal-hod or similar article, substantially as herein described and illustrated.

In testimony whereof I have hereunto set my signature in the presence of two subscribing witnesses.

CHARLES DONAGHY.

Witnesses:

J. WALTER DOUGLASS,
THOMAS M. SMITH.
